[57] **CLAIM**

The ornamental design for a closet shelf, as shown and described.

DESCRIPTION

FIG. 1 is a left side elevational view of a closet shelf showing my new design;

FIG. 2 is a reduced top, front, and left side perspective view thereof;

FIG. 3 is a rear elevational view thereof;

FIG. 4 is a front elevational view thereof;

FIG. 5 is a top plan view thereof;

FIG. 6 is a bottom plan view thereof; and,

FIG. 7 is a fragmentary vertical cross-sectional view thereof, taken along line 7—7 of FIG. 2.

The shelf is shown broken-away in the views to indicate indeterminate length.
